(57) CLAIM

The ornamental design for a singing bowl, as shown and described.

DESCRIPTION

FIG. 1 is a front perspective view of a singing bowl;
 FIG. 2 is a top view of the singing bowl of FIG. 1;
 FIG. 3 is a bottom view of the singing bowl of FIG. 1;
 FIG. 4 is a front view of the singing bowl of FIG. 1; and,
 FIG. 5 is an environmental view of the singing bowl of FIG. 1.

The broken lines in the drawings illustrate portions of the singing bowl and form no part of the claimed design.
